C. W. BOOTH

UNCOUPLING DEVICE FOR CAR COUPLERS

Filed April 10, 1922

Inventor
Charles W. Booth
By W. E. Waldo, Atty.

UNITED STATES PATENT OFFICE.

CHARLES W. BOOTH, OF CHICAGO, ILLINOIS.

UNCOUPLING DEVICE FOR CAR COUPLERS.

Application filed April 10, 1922. Serial No. 551,050.

To all whom it may concern:

Be it known that I, CHARLES W. BOOTH, a citizen of the United States, and a resident of Chicago, in the county of Cook and State 5 of Illinois, have invented an Improved Uncoupling Device for Car Couplers, of which the following is a specification.

This invention relates to uncoupling devices for car couplers and relates particularly to the link which connects the locking pin of the coupler with the uncoupling lever.

The object of the invention is to provide an improved link for the purpose specified, 15 which conforms to M. C. B. and A. R. A. requirements, is simple and relatively inexpensive in construction, strong, durable and effective for its designed use.

To effect the object of the invention, my 20 improved link comprises the various features and details of construction herein-after described and claimed.

In the accompanying drawings, in which 25 an uncoupling link of my invention is fully illustrated,

Figure 1 is a side view of an uncoupling device embodying a link of my invention, shown as applied in use to a standard type of vertical plane coupler, the link being 30 shown in position corresponding to locking position of the coupler locking pin.

Figure 2 is a detached side view of the link, on an enlarged scale, showing the link members in extended relation.

Figure 3 is a view from the left hand side 35 of Fig. 2; and

Figure 4 is a top plan view of the link as shown in Fig. 2.

In Fig. 1 of the drawing, I have, for purposes of clear and definite illustration, shown a railroad car, indicated at A, equipped with a usual type of vertical plane coupler B and an uncoupling device C embodying a link of my invention, designated 45 as a whole D, for connecting the uncoupling lever c with the locking pin b. Excepting as regards the construction of the link D, said coupler B and uncoupling device C merely exemplify usual or approved forms 50 of couplers and uncoupling devices, respectively, and both thereof will readily be understood by persons skilled in the art from an examination of the drawing without a description thereof in detail.

The link D comprises two members d and

d^1 , flexibly connected in overlapped position by a shackle d^2 through which said link members extend and which is pivotally connected to the overlapping ends thereof so as to permit free endwise movement of said 60 link members relatively to each other.

Formed in the remote ends of the link members d , d^1 , are eyes 1 and 2 which respectively engage corresponding eyes 3 and 4 formed at the end of the uncoupling lever 65 c and in the projecting upper end of the locking pin b .

As shown in Figs. 1 to 4; also, the shackle d^2 engages eyes 5 and 6 formed in the overlapped ends of the link members d , d^1 , said 70 shackle and the eyes 5 and 6 being proportioned to permit desired endwise movement of said link members relatively to each other, preferably without spreading the overlapping ends thereof to an appreciable 75 extent. That is, the over-all dimension of said shackle is less than the distance between the remote sides of the eyes 5 and 6 when the link members are in contact and said eyes are in transverse alignment. Also, 80 said shackle is so proportioned with relation to the overlap of the ends of said link members that it will permit limited angular play or divergence of said link members, but will prevent each thereof from turning 85 around the end of the other.

The proximate and lateral sides of the overlapping end portions of the link members d , d^1 , are flattened—said overlapping end portions being shown as substantially square 90 in cross-section—and the shackle d^2 is so proportioned that, when the parts of the link are assembled, said shackle will prevent said link members from turning, either on their own longitudinal axes or about each 95 other—or, in other words, will maintain said link members in designed operating positions.

To provide for conveniently attaching the eyes 1 and 2 on the link members to the 100 eyes 3 and 4 on the uncoupling lever c and on the locking pin b , said links will preferably be supplied on order with the eyes 1 and 2 open, as shown in dotted lines at 105 7 and 8, Figs. 2 and 3, so that, to finish the connection after said eyes 1 and 2 have been engaged with the eyes 3 and 4, it will be necessary merely to bend the off-set portions of said eyes 1 and 2 into closed position.

The parts of my improved link D, may 110

conveniently be forged from metal bars of suitable size and cross-section or may be formed by stamping the same from solid metal plate of suitable thickness.

5 All connections between the parts of the link D and to the uncoupling lever c and locking pin b are made with sufficient clearance not only to provide for desired freedom of movement in operation without danger 10 of binding, but to prevent the link from "freezing up"—that is from becoming clogged and inoperative by an accumulation of snow, ice or sleet in its connections, which would impair or entirely prevent its 15 operation.

I claim—

1. A link adapted for connecting the operating lever of a car coupler with the locking member thereof, comprising two link 20 members and a member which connects said link members together in overlapped position, said connecting member being pivoted to said link members, the relation being such that said link members will be movable end- 25 wise relative to each other.

2. A link adapted for connecting the op-

erating lever of a car coupler with the locking member thereof, comprising two link members and a shackle through which said link members extend and which has pivotal 30 connection therewith, the relation being such that said link members will be movable endwise relative to each other.

3. A link as specified in claim 2, in which the link members are provided with eyes in 35 their overlapping ends through which the shackle passes.

4. A link as specified in claim 2, in which the link members are provided with eyes in their overlapping ends through which the 40 shackle passes and to which it is loosely fitted, the major inside dimension of the shackle being sufficiently greater than the distance between the adjacent inner sides of the eyes in said link members when said 45 link members are in contact with each other to provide for contemplated endwise movement of said link members.

In testimony that I claim the foregoing as my invention, I have hereunto affixed my 50 signature.

CHARLES W. BOOTH.
